UNITED STATES PATENT OFFICE.

DAVID OPPENHEIM, OF NEW YORK, N. Y., ASSIGNOR TO AMERICAN YVETTE COMPANY, INC., OF NEW YORK, N. Y., A CORPORATION OF DELAWARE.

DESIGN FOR A BEAUTY-PARLOR WALL.

Application filed October 26, 1928. Serial No. 28,656. Term of patent 14 years.

To all whom it may concern:

Be it known that I, DAVID OPPENHEIM, a citizen of the United States, residing in New York, in the county of New York and State of New York, have invented a certain new, original, and ornamental Design for Beauty-Parlor Walls, of which the following is a specification, reference being had to the accompanying drawing of which—

I claim:

The ornamental design for a beauty parlor wall as shown.

DAVID OPPENHEIM.
